UNITED STATES PATENT OFFICE

ALFRED G. NORDMARKEN, OF MINNEAPOLIS, MINNESOTA

WINDOW SCREEN

Application filed December 17, 1929. Serial No. 414,642.

My invention relates to window screens and particularly to window screens adapted to be used in conjunction with double hung windows and has for its object to provide a 5 fastener for the screen by means of which the same may be readily rendered operative or inoperative.

Another object of the invention resides in providing a fastener for detachably 10 curing the free end of the screen to the window frame.

A still further object of the invention resides in constructing said fastener with an angle member adapted to be attached to the 15 screen through one of the flanges thereof.

A feature of the invention resides in constructing the other flange of said angle member with a lip issuing outwardly therefrom and in spaced relation thereto.

20 An object of the invention resides in employing in conjunction with said angle member a plate for attachment to the window frame having a lip extending outwardly therefrom and spaced from said plate, the 25 lips on said angle member and plate being adapted to be received within the respective spaces between said lips and the structures on which the same are formed.

Another object of the invention resides in 30 turning over the extreme edges of said lips to hold the lips from disengagement.

A still further object of the invention resides in constructing on the flange of the 35 angle member having the lip formed thereon a protuberance for engagement by the operator to disengage the lips from one another.

Other objects reside in the novel combination and arrangement of parts and in the details of construction hereinafter illustrated 40 and/or described.

In the drawings:

Fig. 1 is a longitudinal sectional elevational view of a double hung window illustrating an embodiment of my invention applied thereto.

Fig. 2 is an elevational sectional view of a part of the structure shown in Fig. 1 drawn to a larger scale.

Fig. 3 is a fragmentary elevational view 50 of a corner of the sash shown in Figs. 1 and

2 illustrating the method of attaching my invention thereto and drawn to a still larger scale.

Fig. 4 is a cross sectional detail view of the device for attaching the free end of the 55 screen to the window and drawn to an enlarged scale.

Fig. 5 is a perspective view of the screen and supporting structure detached from the window.

Where a permanently attached window screen is employed an appreciable amount of light is excluded. This is particularly true where the screen covering the entire window is used. Furthermore dirt and dust 65 readily accumulate on the screen and upon the exterior of the window making it difficult to clean the window without removing the screen. In my invention these difficulties are overcome due to the fact that the screen 70 may be quickly and readily detached from the structure to which the free end thereof is connected so as to give access to the window from both sides thereof. At the same time the screen is completely concealed when 75 the window is closed giving a maximum amount of light and at the same time protecting the screen.

For the purpose of illustrating an application of my invention I have shown in the 80 drawings an ordinary double hung window which is indicated in its entirety at A. This window comprises a window frame 10 having an upper sash 11 and a lower sash 12. These parts may be constructed in any suitable 85 manner such as is now well known in the art, the particular form illustrated being shown merely for the purpose of indicating the method of installing my invention thereto.

The frame 10 comprises vertical frame 90 members 13 connected together at their upper ends by means of a header 14 and at their lower ends by means of the usual window sill 15. The frame 10 is set into the opening in the building and is attached to the studding 16 thereof in the usual manner. Frame 10 may be constructed with an outer casing 17 and with an inner casing 18 and is provided with the usual inner stop 19, outer stop 20, and parting strip 21. The 100

window A may be further provided with the usual window stool 22 and apron 23 forming a part of the interior casing 18 of said window.

6 The two sashes 11 and 12 are constructed in much the same manner. The sash 11 is formed with stiles 24, an upper rail 25 and a meeting rail 26, while the sash 12 is similarly formed with stiles 27, a meeting rail 10 (not shown) and a lower rail 29. These various stiles and rails are recessed to receive ordinary window panes 30 and 31 which may be mounted therein in the usual manner and sealed through the use of putty or any other 15 suitable means. The upper sash 11 is slidably mounted between the outer stop 20 and the parting strip 21 while the lower sash 12 is slidably mounted between the said parting strip and the inner stop 19. When the 20 sashes are in closed position the rails 29 are received within the respective guides formed between the parting strip 21, the stops 19 and 20 and the stool 22, while the meeting rails of the sash join one another to completely close the window in the usual manner. 25

The screen used in conjunction with my invention is preferably of fabric or flexible wire and is coiled about a suitable roller and attached at one end thereto. If desired 30 screens may be utilized for both the upper and lower sashes or for only one of these sashes as the occasion demands. In the drawings I have illustrated a screen 32 in conjunction with the lower sash 12, and a 35 screen 33 used in conjunction with the upper sash 11. The screen 32 will first be described in detail.

The screen 32 is attached to a roller 34, one end of which is shown in detail in Fig. 3. 40 This roller is constructed with a bore 35 at one end thereof in which is disposed a rod 36 having coiled about it a helical spring 37. The spring 37 is attached at one end to the rod 36 and at its other end to the roller proper so as to permit of winding up the roller upon holding the rod stationary as is customary with ordinary window shade rollers. At the extreme end of the roller 34 is attached to it a plate 38 which forms a bearing 50 for the end of the rod 36. This plate is secured in position upon the end of the roller through a ferrule 39. The extreme end of the rod 36 is formed with a flattened pin 40 which is adapted to be held from rotation 55 and serves to mount the shade in the customary manner. The other end of the roller 34 may be provided with another pin or trunnion (not shown) for supporting the shade roller such as is now in common use, or a device 60 similar to or having similar functions to the rod 36 may be employed for this purpose, either with or without the helical spring. The roller 34 is constructed without the usual pawls employed for holding 65 the roller in locked position so that when

the spring 37 is first tensioned the said roller will at all positions of the sash cause the screen to wind up or coil about the same. In this manner when the screen is attached at its lower end to the window sill, the same 70 automatically winds up on the roller 34 as the sash is raised and lowered to cause the screen at all times to fill the opening between said sash and sill and to be completely concealed within the space in which the said roller is mounted when the sash is fully closed.

The roller 34 is mounted upon a frame structure best shown in Fig. 5 and indicated in its entirety at 41. This frame structure includes an elongated plate 42 of the exact length of the rail 29 of sash 12 which plate has bent outwardly therefrom two end members 43 and 44 of a depth equal to the thickness of the said rail. A flange 45 may be turned inwardly from the plate 42 to somewhat stiffen and reinforce the same, though it will become presently apparent that the depth of the said flange cannot be such as to entirely preclude the flexing of this plate. 85 In an appropriate position on each of the end members 43 and 44 and disposed the same distance from the plate 42 are formed two inwardly extending, facing lugs 46 which may be formed by pressing the metal of the 90 end members 43 and 44 out of plane thereof. Centrally disposed within these lugs are openings 47 (Fig. 3) which are adapted to receive the pins 40. At the end of the roller where the spring 37 is located, the opening 95 47 is constructed elongated to receive the flattened pin, so as to hold the rod 36 from rotation. Where a similar structure is used at the other end of the roller a similarly formed opening may be employed. However, where 100 a circular pin is employed at the opposite end of the roller serving as a trunnion for journaling the same, a circular hole would have to be employed for this purpose. Such construction being well known in the art has 105 not been illustrated.

The plate 38 situated at the end of the roller 34 is disposed inwardly of the end of the ferrule 39. This provides a space for the reception of the lug 46 bringing the ends of the roller substantially flush with the inner surfaces of the end members 43 and 44 and the end of the pins 40 substantially flush with the exterior surfaces of the said end members. This permits of utilizing a screen of 110 substantially the entire width of the window so as to completely cover the opening through the window and preclude the entrance of insects through the window opening.

The frame structure 41 carrying the roller 115 34 and screen 32 is mounted on the lower rail 29 of the window 12. This rail is formed with a rabbet 48 open at the rear and lower edge of the window sash. The frame 41 is so disposed that the plate 42 overlies the rear 120

of the rail 29 and closes the opening along the rear side of the rabbet 48. When so disposed the shade and roller are received within the rabbet 48, being entirely concealed from view as best brought out in Fig. 2.

In installing the screen and supporting structure the plate 42 of frame 41 is first flexed or sprung sufficiently to spread apart the two end members 43 and 44 which permit of inserting the pins 40 of the roller 34 into the proper openings 47 in said end members provided for the reception of said pins. The screen proper is at the same time disposed between the rod 65 and the plate 42. Upon releasing the frame structure the end members 43 and 44 spring back into place so as to hold the roller 34 supported in proper position. The entire frame structure may be then applied to the rail 29 of the window sash and secured thereto through screws 49 insertable through openings 50 in the said plate and end members and screwed into the sash proper. In the installation of the sash a groove 51 is formed in the rail 29 for the reception of the flange 45 of the frame structure and if desired the frame 41 may be made slightly smaller and the side and ends of said rail may be recessed to receive the plate 42 and the end members 43 and 44 so as to cause the same to lie flush with the exterior surface of the sash. When the supporting structure is so installed the end 52 of the screen may be projected through the open lower portion of the rabbet 48 to be extended or retracted therefrom as desired.

The free end 52 of the screen 32 may be detachably secured to the window sill 15 so that when the sash is raised and lowered the said screen may be wound or unwound upon the roller to maintain the space between the rail 29 and the sill 15 covered. Upon the extreme end 52 of the said screen is attached an angular attaching strip 53 best shown in Fig. 4 which is constructed with a vertical flange 54 and a horizontal flange 55. The extreme edge of the flange 54 indicated at 56 is doubled back upon itself to receive and hold the extreme end 52 of the screen 32 attached thereto. The other flange 55 of said attaching member is doubled back upon itself to form a lip 57 which is spaced from the said flange. Cooperating with the attaching member 53 is another attaching member 58 which comprises a plate 59 adapted to be secured to the window sill 15 through a number of screws 60. This plate is doubled back upon itself along the length thereof to form a second lip 61 spaced from the said plate 59 in a similar manner to the lip 57. The two lips 57 and 61 may be interlocked by sliding the attaching member 57 along the plate 59 in an outward direction causing the parts to assume the position shown in Fig. 4. For assisting in retaining the attaching member 53 interlocked with respect to the attaching

member 58 the lips 57 and 61 have the extreme edges 62 and 63 thereof turned inwardly to prevent the accidental disengagement of the said lips as long as tension is applied to the screen 52. Due to the helical spring 37 the said screen is always under tension and the screen remains securely attached at its lower end to the sill proper.

For facilitating the disengagement of the lower end of the screen the flange 55 is constructed with a hump 64 standing upwardly therefrom which may be engaged by the finger of the user for assisting in withdrawing the lips 57 and 61 from engagement with one another. When it is desired to detach the screen the attaching member 53 is drawn inwardly toward the stool 22 until the edges 62 and 63 are free from one another. Upon releasing the screen the tension of spring 37 causes the entire screen to become wound up and wholly confined within the rabbet 48.

In order to prevent rain from remaining within the space between the lip 61 and the plate 59 the said plate is constructed at the bend thereof with a number of holes 70 from which water entering the said space may be drained.

In the attachment of the screen to the window frame the attaching member 58 is located in close proximity to the parting strip 21 so as to cause the screen 32 to lie along the edge of said parting strip and prevent the intrusion of insects. As the screen unwinds from the roller 34 the coiled portion thereof becomes smaller in diameter causing the distance between the screen and said parting strip to vary. To overcome this disadvantage I employ a rod 65 which is attached to the end members 43 and 44 of the frame structure 41 and which guides the movement of the screen 32 so that the same at all portions thereof lies as close to the parting strip 21 as possible. This rod also serves as a stop for preventing the free end of the screen when released from entering into the rabbet 48 in such a manner as to render the same inaccessible and to preclude the withdrawal of the said screen from said rabbet when it is desired to put the same into operation.

The screen 33 employed with the upper sash 11 is constructed and mounted in exactly the same manner as the screen 32. For this reason this structure has not been illustrated in detail. This screen is similarly mounted upon a roller 66 carried by a frame structure 67 similar to the frame structure 41. In this device the plate member 68 corresponding to the plate 42 is somewhat shorter than said latter plate. The reason for this is that the roller 66 instead of being attached to the rail 25 of sash 11 is attached to the upper portion of the frame 13 while the free end of the said screen is secured to the rail 25 of the sash proper. This is for the purpose of preventing water from draining

upon the screen and the supporting structure therefor in a manner to cause the same to deteriorate and cease to function. The frame 67 is of a width slightly larger than the width of the sash proper and is received within the guide formed between the parting strip 21 and the outer stop 20. The frame structure 67 may be secured to the window frame through screws 69 and is in other respects identical with the frame structure carrying the roller 34. Upon the free end of the screen 83 is secured an attaching member not shown in detail, identical with the attaching member 53 which cooperates with another attaching member identical with the attaching member 58 secured to the rail 25 at the bottom of a rabbet 170 formed in the upper portion thereof. This rabbet is of such a size as to receive the roller 66 and screen 33 when the sash 11 is elevated. When so disposed the plate 68 of the supporting structure 67 covers the rear side of the said rabbet while the end members of said supporting structure corresponding to the end members 43 and 44 of the supporting structure 41 cover the ends of the said rabbet.

For the purpose of providing a tight closure between the two sash 11 and 12 when in open position a sealing strip 71 is employed which is attached to the under side of the meeting rail 26 of sash 11 and which projects up to window pane 31. This strip serves to maintain the space between the sash closed so as to prevent intrusion of insects there-

through.

My invention is highly advantageous in that the same can be constructed at an economical cost. The sheet metal parts forming the supporting structure for roller can readily be applied to the window frame and sash and serve to close the rabbet formed in the sash for the reception of the roller. The end of the screen may be quickly detached or attached to the attaching device so as to bring the same into inoperative or operative position as desired. The guide rod serves to hold the screen close to the parting strip or stop so as to effect a tight closure and at the same time holds the end of the screen from entering the rabbet a distance sufficient to render the same inaccessible. The device is positive in action and cannot readily get out of order.

Changes in the specific form of my invention, as herein described, may be made within the scope of what is claimed without departing from the spirit of my invention.

Having described my invention, what I claim as new and desire to protect by Letters Patent is:

1. A fastener for screens comprising an elongated angle member adapted to be secured to the screen through one of the flanges thereof, the other of the flanges of said angle member having a lip issuing outwardly

therefrom and spaced from said flange, a plate for attachment to the member to which the screen is to be fastened, a lip formed along an edge of said plate and spaced therefrom, said lip extending in the opposite direction from the lip on said angle member, said lips being adapted to be received within the respective spaces between said lips and the structures from which they issue to hold the screen fastened, said lips having the extreme edges thereof turned over to engage one another so as to hold the lips from disengagement.

2. A fastener for screens comprising an elongated angle member adapted to be secured to the screen through one of the flanges thereof, the other of the flanges of said angle member having a lip issuing outwardly therefrom and spaced from said flange, a plate for attachment to the member to which the screen is to be fastened, a lip formed along an edge of said plate and spaced therefrom, said lip extending in the opposite direction from the lip on said angle member, said lips being adapted to be received within the respective spaces between said lips and the structures from which they issue to hold the screen fastened, the flange having the lip formed thereon being provided with a protuberance for engagement by the operator to disengage said lips from one another.

In testimony whereof I have affixed my signature to this specification.

ALFRED G. NORDMARKEN.
